(57) **CLAIM**

The ornamental design for a computer attachment for photographs and information cards, as shown and described.

DESCRIPTION

FIG. 1 is a perspective view of a computer attachment for photographs and information cards showing my new design; FIG. 2 is an enlarged perspective view thereof;

FIG. 3 is a front elevational view thereof;

FIG. 4 is a rear elevational view thereof;

FIG. 5 is a top plan view thereof; and,

FIG. 6 is a bottom plan view thereof.

The broken lines are included for the purpose of showing environment and form no part of the claimed design.

1 Claim, 3 Drawing Sheets

FIG. I

FIG. 2
